UNITED STATES PATENT OFFICE.

ISAIAS ZEPEDA, OF SAN ANTONIO, TEXAS.

TRANSPOSITION DEVICE.

Application filed August 2, 1922. Serial No. 579,281.

To all whom it may concern:

Be it known that I, ISAIAS ZEPEDA, a citizen of Mexico, residing at San Antonio, in the county of Bexar, State of Texas, have 5 invented certain new and useful Improvements in Transposition Devices; and I do hereby declare the following to be a full, clear, and exact description of the invention, such as will enable others skilled in 10 the art to which it appertains to make and use the same.

This invention relates to new and useful improvements in transposition devices, and particularly to transposition devices 15 for pianos.

One object of the invention is to provide a simple and cheap device of this character by means of which the keyboard of a piano may be shifted from right to 20 left, and vice versa, to raise or lower the pitch, for the accommodation of instruments and voices.

Another object is to provide a device of this character which may be readily applied 25 to the ordinary piano, without radical modifications to the piano, and which will not alter the appearance thereof.

Other objects and advantages will be apparent from the following description when 30 taken in connection with the accompanying drawings.

In the drawings:

Figure 1 is a front elevation of a portion 35 of a piano, with a portion of the front board, of the keyboard removed.

Figure 2 is a vertical sectional view on the line 2—2 of Figure 1, passing longitudinally through the center of one of the white keys.

Figure 3 is a bottom plan view of the 40 slidable board, which moves the keyboard of the piano, showing the gear and rack connections.

Referring particularly to the accompanying drawing, 10 and 11 represent the longitudinally extending strips, below the keyboard of the piano, each strip having a longitudinally extending groove in its inner vertical face, as shown at 12. Disposed 45 longitudinally beneath the keyboard of the piano, and having the ribs 13 on its longer edges riding in the said grooves 12, is a board 14. This board supports the inner and outer rows 15 and 16, of vertical pins, the former being the fulcrums of the key-levers 17, while the latter enter the lower

faces of the key-levers to prevent horizontal rocking movement thereof, as will be more clearly explained later herein. Each of the key-levers 17 is separated at 18, from 50 the main portion thereof, at points immediately in rear of the upper front board of the music shelf of the piano. In the bottom wall of the channel beneath the keyboard, and directly below the front and rear edges of the board 14, are the upwardly impelled spring pressed pins 19, which are arranged to enter the openings or recesses 20, formed in the lower face of the said board, for the purpose of maintaining the 55 board against accidental longitudinal movement.

Formed transversely in the inner end of the outer, or ivory covered portion of each key-lever, is a channel, or kerf 21, which receives the flat portion of the stem 22, which is secured in the forward end face of the rear portion of the key-lever. When the stems are properly disposed in the kerfs, the key-levers may be operated in the 60 usual manner, rocking the entire lever on the front pin 15. When the board 14 is moved longitudinally beneath the keyboard, the outer portions of the key-levers will be moved therewith, by virtue of the engagement of the pins 15 and 16 within the lower 65 face of the outer or playing portions of the levers, the spring pressed pins 19 entering the openings or recesses in the bottom of the board 14. It will be noted that the pins 70 19 are regularly spaced at distances equal to the width of a key-lever, so that upon shifting the board 14, the operator will be 75 able to know when the stems 22 properly register with the kerfs of the front portions of the key-levers.

Properly supported in a vertical position in the bottom of the channel beneath the keyboard, and extending downwardly therethrough, where it is provided with a 80 transverse handle 23, is a shaft 24, the same having on its upper end a gear 25 which meshes with a rack 26 secured to the lower face of the board 14, adjacent the front 85 longer edge thereof. By this means, the board 14 may be shifted to the right or left, according to the desire of the operator, as to whether the pitch is to be raised or lowered. Also, it will be readily understood 90 that, when the board 14, and the keyboard are shifted, the front portions of the key-levers engage with different inner key-

lever portions, with the result that when one of the keys is struck, a different inner key-lever will be operated, and a higher or lower tone produced.

5 Great difficulty is sometimes experienced in tuning some instruments, and especially wind instruments, to a piano, because of the fact that the piano is of too low a pitch, and the slides, by means of which the instrument is tuned, cannot be drawn out far enough. Also, some singers find the pitch of a piano too high for their voices. In the first case, the player of the piano simply shifts the keyboard toward the right, with 10 the result that the pitch is raised. This may be done to raise the pitch one, two, or three tones, as desired. In the other case, the keyboard must be shifted to the left, to lower the pitch, to accord with the range 15 of the singer's voice. When the board is shifted in either direction, the rear pins 16 serve to prevent the front portions of the key-levers from rocking horizontally on the front pins 15, and getting out of alignment 20 with the rear portions of the levers.

The block 27, at the left-hand end of the keyboard of the piano, is formed with a cavity 28, into which the corresponding end 30 of the board 14, and of the keyboard, are arranged to move, when the board is shifted toward the left, as when lowering the pitch. The block 29, at the right-hand end of the keyboard is similarly formed with a cavity 30, to accommodate the corresponding end 35 of the keyboard, when the same is shifted toward the right, as when raising the pitch.

In operating the transposition device, the operator need only grasp the handle 23 and rotate the shaft 24 toward the right or 40 left, as the case may be, until the pins 19 snap into the proper openings of the board 14.

What is claimed is:

1. A transposition device for pianos including key-levers having inner sections and outer sections, the outer sections having transverse kerfs in their inner ends opening through the sides of the sections and sockets in their lower faces, the inner sections having flat stems engaged in the said kerfs and 45 arranged to pass into the kerfs of adjacent outer sections and slidable means having pins engaged in said sockets for shifting the outer sections transversely of the inner sections and into engagement with the stems of other inner sections.

2. A transposition device for pianos including key-levers having inner and outer sections, a slidable member rockably supporting the playing portions of the levers, 60 guides on the piano supporting the slidable member, flat stems projecting from the outer ends of said inner sections, the inner ends of the outer sections having transverse narrow openings slidably receiving said stems, 65 detents on the piano engaged with the slid-

able member for releasably holding the slid-
able member in position with the openings
of the outer sections of the levers in registry
with the stems of the inner sections thereof,
and means for shifting the slidable member. 70

3. A transposition device for pianos in-
cluding a keyboard the key levers of which
include inner relatively stationary sections
and outer movable playing sections, slide-
able connections between the sections, a slide-
able member disposed longitudinally be-
neath the keyboard and having openings in
its lower face and a toothed rack, spring
pressed pins engaged in the openings, a gear
engaged with the rack, fulcrum means for 80
the playing portions of the levers carried
by the slidable member, means on the slide-
able member and engaging with the last-
named portions of the levers for preventing
lateral pivotal movement thereof, means 85
at the ends of the piano for receiving the
ends of the keyboard when the latter is
shifted, and means on the gear for rotating
the same.

4. A transposition device for pianos in-
cluding key levers having inner and outer
sections, the outer sections having kerfs in
their inner ends opening through the sides
of the sections and having sockets in their
lower faces, the inner sections having stems
engaged in said kerfs and arranged to be
received in kerfs of adjacent outer sections,
slidable means for moving the outer sec-
tions transversely of the inner sections and
into engagement with said stems of other
inner sections, selectively, said slide-
able means having means for engagement in said
sockets and means for moving the slide-
able means. 95

5. A transposition device for pianos in-
cluding key levers comprising inner and
outer sections having connections for trans-
verse slideable movement in a common plane,
guides, a slideable member supported in the
guides and operatively connected with said
outer sections of the key levers, and means
for moving the slideable means for engaging
the said outer sections with adjacent inner
sections, selectively. 105

6. A transposition device for pianos in-
cluding key levers comprising stationary
and movable sections, the latter of which
are movable into and out of operative en-
gagement with adjacent stationary sections
at opposite sides thereof, selectively, and
while remaining in the same plane there-
with, means for moving said movable sec-
tions, and means for moving the moving
means. 115

7. A transposition device for pianos in-
cluding key levers comprising inner sta-
tionary sections and outer sections movable
transversely of the stationary sections into
and out of position in alignment with adja-
cent stationary sections, selectively, and 125
130

means for moving said outer sections, and means for releasably holding the outer sections in such alignment.

8. A transposition device for pianos including key levers comprising inner stationary sections and outer movable sections, the latter sections being movable transversely of and into and out of alignment with adjacent stationary sections, selectively, 10 means on the stationary sections engaged with the movable sections for maintaining the latter sections in the same plane as that

of the stationary sections during such movement and during the normal operation of the key levers, means for moving the movable sections, and means for releasably holding the movable sections in such selective alignment. 15

In testimony whereof, I affix my signature in the presence of two witnesses.

ISAIAS ZEPEDA.
